STARTING SWITCH FOR ELECTRICAL
DISCHARGE LAMPS

Paul L. Betz, Baltimore, Md., assignor to Consolidated Gas Electric Light and Power Company of Baltimore, Baltimore, Md., a corporation of Maryland

Application February 21, 1942, Serial No. 431,893

19 Claims. (Cl. 315—100)

This invention relates to starting switches for electrical discharge lamps, such as fluorescent lamps, and more particularly to starting switches which are so constructed that the starting operations of the switch are discontinued automatically if the lamp is defective or otherwise unable to maintain the electrical discharge.

Generally stated, an electrical discharge lamp comprises a pair of spaced electrodes in an envelope containing a gas or mixture of gases at a suitable pressure. The electrodes are adapted to be heated to incandescence by passage of an electric current therethrough, and are in circuit with a starting switch whose function is to momentarily connect said electrodes in series to bring them to incandescence and then interrupt the circuit through the electrodes, whereupon the resultant transient voltage, due to the presence of a reactor in another part of the circuit, initiates a discharge within the lamp.

As the lamp approaches the end of its useful life, the decrease of electron emission from the electrodes makes the starting of the lamp more and more difficult, until a point is finally reached at which it is impossible to maintain the electrical discharge. Thereafter, upon energizing the lamp, the starting switch continues to go through the cycle of starting operations above referred to, successively making and breaking the filament-heating circuit, and if the lamp fails to start, this continued operation of the starting switch may result in damage to the switch itself or to the transformer or to the reactor associated therewith.

It is an object of the present invention to provide a starting switch for electrical discharge lamps with means whereby, after a limited number of unsuccessful attempts to start a lamp, the starting operation is discontinued automatically.

A further object of the present invention is to provide a starting switch of the character referred to with means for discontinuing the starting operation of the switch under abnormal conditions and which, upon deenergization, is automatically restored to a condition for normal operation.

Another object of this invention is to provide a starting switch for electrical discharge lamps with safety means which discontinues the operation of the starting switch if, after a predetermined number of cycles, the lamp fails to start.

Another object of this invention is to provide a starting switch of the character referred to with a thermally operated switch which is normally inoperative to interrupt the circuit but

which, under abnormal conditions, is opened to interrupt the starting circuit.

Another object of this invention is to provide a starting switch as last characterized with means for maintaining the switch in said open position as long as the starting circuit is energized.

Another object of this invention is to provide a starting switch for electrical discharge lamps which fulfills the foregoing objects and which at the same time is of such simplicity that it may be readily embodied in commercial starting switches for electrical discharge lamps without unduly complicating the circuit arrangements or the associated structure.

Other objects of the invention will appear as the description of the invention proceeds.

The invention is capable of receiving a variety of mechanical expressions, two of which are illustrated on the accompanying drawing, but it is to be expressly understood that the drawings are for purposes of illustration only, and are not to be construed as a definition of the limits of the invention, reference being had to the appended claims for that purpose.

In the drawing, Figs. 1 and 2, respectively, illustrate diagrammatically circuit arrangements for starting switches for electrical discharge lamps embodying the present invention.

In the embodiment of Fig. 1 an electrical discharge lamp, as a fluorescent lamp, is diagrammatically indicated at 10, the same having filamentary electrodes 11 and 12, respectively, connected through wires 13 and 14 to the terminals of a transformer 15 having an input represented

35 by the leads 16. In series with the transformer 15 and the electrodes is a suitable reactor 17 for initiating the discharge in the lamp in accordance with principles well understood in the art. The electrodes 11 and 12 are also in series through wires 18 and 19, respectively, with the terminals 20 and 21 of the starting switch now to be described.

The improved starting switch embodying the present invention is connected with said terminals 20 and 21. Connected with terminal 20 through wire 22 is a bimetallic contact arm 23 provided with contacts 24 and 25. A second bimetallic contact arm 26 is provided with a contact 27 for co-operation with the contact 24 and a third bimetallic contact arm 28 is provided with a contact 29 for co-operation with the contact 25. Also connected to the terminal 20 in parallel with the wire 22 is a suitable resistor 30 constituting a heating element in heat interchanging relationship with the contact arm 23, said heating ele-

ment 30 being connected to a wire 31 to which is connected wire 32 from the contact arm 26. Wire 32 includes a relatively small resistor 33, or in place of using a separate resistor 33, the material of the contact 27 may be such as to provide the necessary resistance in series with the arm 26. Another resistor 34 is connected in series with the contact arm 28, and constitutes a heater in heat interchanging relation with arm 28, being shown as surrounding the arm 28. Resistor 34 is connected to the wire 31 by wire 35. Contact arm 28 also has suitably formed thereon or attached thereto a finger 36 for a purpose to be described.

Wire 31 is connected to a bimetallic contact arm 37 carrying a contact 38 in position to cooperate with a contact 39 on a bimetallic contact arm 40. Contact arm 40 is connected to the terminal 21 by wire 41. Connected in shunt around the contact arms 37 and 40, and their contacts 38 and 39 is a resistor 42 constituting a heating element in heat interchanging relationship with the contact arm 40, said resistor 42 being connected to the wire 31 by wire 43 and to the lead wire by wire 44.

A condenser 45 is connected between the terminals 20 and 21 by a connection 46 to wire 22 and a connection 47 to wire 41, whereby said condenser is electrically in parallel with the other circuits of the starting switch and functions to absorb energy incident to the separation of the contacts of the starting switch as understood in the art.

When the lamp is deenergized the several contacts above referred to are in the relative positions shown in Fig. 1, i. e., the circuit is open between contacts 25 and 29 but closed at contacts 24, 27 and at contacts 38, 39. Upon supplying energy at the input 16 to transformer 15 the current flows through the circuit consisting of reactor 17, wire 13, electrode 11, wire 18, terminal 20, wire 22, bimetallic contact arm 23, contacts 24, 27, bimetallic contact arm 26, resistor 33, wires 32 and 31, bimetallic contact arm 37, contacts 38, 39, bimetallic contact arm 40, wire 41, terminal 21, wire 19, electrode 12 and wire 14 to the opposite side of the transformer 15. A portion of the current is also shunted through the parallel circuit including heater element 30 and its connecting wire 31. Upon energizing the circuits as above referred to, heat from heater 30 and heater 33 causes contact arm 23 to flex and open the circuit between contacts 24 and 27. This interrupts the current flowing through the above described circuit including the incandescent lamp electrodes 11 and 12, and gives rise to a transient voltage across the electrodes of the lamp due to the action of the reactor 17. If the lamp operates properly an electrical discharge will be established between electrodes 11 and 12, and the voltage drop across these electrodes may be of the order of one-half the voltage appearing across the electrodes prior to the separation of the contacts 24 and 27. Heater 30 is so proportioned that the I^2R loss therein when the lamp is operating is sufficient to maintain contact arm 23 in its intermediate position so that the contacts 24 and 25 are out of contact respectively with the contacts 27 and 29, thereby maintaining the circuit open at this point. The current can continue to flow from the resistor 30 through wire 31, contacts 38 and 39 and wire 41 as above described. This is the equilibrium condition for a lamp that is operating properly.

Should the lamp fail to ignite for any reason, as for example if the lamp is defective due to

the loss of electron emission from the electrodes 11 and 12, the transient voltage between these electrodes may initiate a discharge which will not be maintained, or the discharge may not be initiated. Under this condition the high voltage will again be applied to the heater 30 and due to generated heat the contact arm 23 will continue to move away from its initial position and toward that position in which an electrical circuit is established between the contacts 25 and 29. Upon closure of the contacts 25 and 29 the electrodes 11 and 12 will again be energized, the current now flowing from the wire 18 and terminal 20 through wire 22, contact arm 23, contacts 25 and 29, contact arm 28, resistor 34 and wire 35 to the wire 31, from which the remainder of the circuit is as first above described. This just described circuit, as will be observed, is in parallel to the heater 30 and its wire 31, and as a consequence the I^2R loss in heater 30 is reduced, causing contact arm 23 to cool and flex toward its original position to interrupt the circuit at the contacts 25, 29. This interruption of the circuit again causes a transient voltage to be applied between the electrodes 11 and 12 of the lamp, and a further attempted start is made.

If this renewed effort to start the lamp is ineffective, as because the lamp is defective or the discharge cannot otherwise be maintained, reestablishment of the circuit only through heater 30 will again cause contact arm 23 to flex to re-engage contacts 25 and 29, and at each opening and closing of the contacts 25 and 29 as just described a new starting impulse will be applied to the lamp.

Also, at each engagement of the contacts 25 and 29 an impulse of current flows through the heater 34 to cause the associated contact arm 28 to flex toward the left as viewed in the drawing. The finger 36 associated with contact arm 28 is of such length and so located with respect to contact arm 40 that after a predetermined number of impulses of current through the heater 34, finger 36 will engage contact arm 40 and flex it to the left, as viewed in the drawing so as to open the circuit at contacts 38 and 39, thus mechanically interrupting the circuit at said contacts. When this circuit is so opened at the contacts 38, 39, current may still flow through the heating element 42 in shunt with the normally closed circuit through the contacts 38 and 39. Under normal operation, when said contacts are in engagement, the amount of current flowing through the heater 42 is insufficient to cause flexure of the arm 40 sufficiently to disengage the contacts 38 and 39, but when the contacts 38 and 39 have been separated by the mechanical operation of the finger 36 all current flowing in the circuit must flow through the heater 42 which, by reason of its association with arm 40, tends to cause said arm to flex toward the left as viewed in the drawing, so that a position of equilibrium is established by said heater 42 wherein the quantity of heat transmitted by the heater 42 to the arm 40 is sufficient to hold the arm 40 flexed with its contact 39 separated from the contact 38.

As soon as the contacts 38 and 39 are separated the operation of the starting switch is discontinued, and when the position of equilibrium of the bimetallic arm 40 is reached owing to the heat from the resistor 42, the starting switch is locked out of operation owing to the separation of the contacts 38 and 39, current continuing to flow through resistor 30, wire 31, wire 43, resistor

42 and wire 44, but the quantity of heat involved at heater 30 being only sufficient to hold bimetallic arm 23 in its intermediate position with its contacts 24 and 25 respectively out of engagement with contacts 27 and 29, but the heat evolved in the resistor 42 being sufficient to maintain bimetallic arm 40 in its aforesaid open circuit position. This condition will continue until the cause of the difficulty is removed.

This automatically operating starting switch as described has the advantage that it resets automatically upon deenergizing the circuit. Upon interrupting the input to the transformer 15, or upon removing lamp 10 from its socket, the current through the starting switch is interrupted. Thereupon, the heating elements 30 and 42 cool and reestablish the circuit through contacts 24 and 27, on the one hand, through contacts 38 and 39, on the other hand, so that the starting switch is restored to its condition for normal operation upon the next energization of the same.

Contact arms 26 and 37 are made of bimetal so as to function as compensation elements responding to the temperature of the ambient. Thus an increase of temperature in the ambient would tend to flex arm 23 to the left as viewed in the drawing irrespective of the operation of heater 30 but arm 26 is so constructed as to compensate for such increase in ambient temperature and retain contacts 24 and 27 in engagement. Similarly arm 37 compensates for the action of the ambient on arm 40.

In the embodiment shown in Fig. 2, wherein the same parts are designated by the same reference characters, bimetallic arm 23 is connected to terminal 20 through wire 22, and carries contacts 24 and 25, but the contacts 48 and 49, which correspond respectively with contacts 27 and 29 in Fig. 1, are fixed relative to each other by contact arms 50 and 51. The electrical circuit through contact arm 50 includes a resistor 52 but, as above indicated, contact 48 may be made of a material having a relatively high resistance so that a separate resistor 52 is unnecessary. The contact arms 50 and 51 are moved as a unit by a bimetallic contact arm 53 which is in circuit with the contact arm 50 and contact 48 but is electrically insulated from the contact arm 51 and its contact 49. Contact arm 53 is connected by wire 54 to wire 55 leading from resistor 56 which is a heater in heat interchanging relationship with the contact arm 23 and connected at its opposite end to wire 22, so that, as in the embodiment of Fig. 1, the circuit through resistor 56 and wire 55 is in parallel with the circuit through contact arm 23, contacts 24 and 48, arm 50, resistor 52, contact arm 53 and wire 54. Contact arm 51 is connected in series with a resistor 57 constituting a heater for the arm 53 and here shown as surrounding but electrically insulated from said arm 53, resistor 57 being connected to wire 55 by wire 58.

As in the embodiment of Fig. 1, bimetallic contact arm 53 carries, in any suitable way, a finger 36, adapted to engage and operate bimetallic contact arm 40 carrying contact 39 which cooperates with contact 38 on a bimetallic contact arm 37 in series with the wire 55. Contact arm 40 is in series with the wire 41 leading to the terminal 21, and in shunt around the contacts 38, 39 is a resistor 42 connected by wires 43 and 44 with the wires 55 and 41, respectively.

On energizing transformer 15, the current flows in the circuit including the reactor 17, wire 13,

electrode 11, wire 18, terminal 20, wire 22, contact arm 23, contacts 24, 48, contact arm 50, resistor 52, contact arm 53, wires 54 and 55, contact arm 37, contacts 38 and 39, contact arm 40,

wire 41, terminal 21, wire 19, electrode 12 and wire 14 back to the transformer 15. The current flowing in this circuit heats the electrodes 11 and 12 to incandescence while current flowing through resistors 56 and 52 raises the temperature of the resistors to flex arm 23 and separate the contacts 24, 48. This interruption of the heating current through the electrodes 11 and 12 causes a high transient voltage to be applied between said electrodes, and if lamp 10 is operative an electrical discharge is initiated and sustained between said electrodes. While the lamp is operating the voltage drop across the discharge may, as above noted, be approximately one half of the voltage across these electrodes when no electrical discharge exists, and therefore, during operation of the lamp, the reduced voltage applied to heater 56 causes a heat dissipation that is sufficient and appropriate to maintain arm 23 flexed with the contacts 24 and 25 thereon intermediate the contacts 48 and 49.

Should the discharge of the lamp not be maintained, the increased voltage is again applied to the heater 56, causing arm 23 to further flex toward the left as viewed in the drawings until contact 25 engages contact 49. Thereupon, the current flows from wire 22, through contact arm 23, contacts 25 and 49, contact arm 51, resistor 57, wire 58 and wire 55. Thereby a shunt circuit is established across the heater 56 which causes said heater to cool and permit the contact arm 23 to flex toward the right, as viewed in the drawing, to open the circuit at 25, 49. This again gives a transient voltage across the electrodes 11, 12 in a new attempt to initiate the discharge of the lamp. If the lamp does not start, increased voltage is applied to the heater 56, causing contact arm 23 to reestablish a circuit through contacts 25 and 49, and this operation is repeated through a number of cycles.

If the lamp is defective so that a discharge is not sustained between its electrodes, each closure of the circuit at contacts 25 and 49 causes an impulse of current to flow through the resistor 57, and thereby the bimetallic contact arm 53 becomes progressively heated to cause the same to flex toward the left as viewed in the drawing. After a predetermined number of actuations the finger 36 engages contact arm 40 to mechanically open the circuit at the contacts 38 and 39. The current now flows in increased amount through the resistor 42 to heat the contact arm 40 and retain the same in its flexed position with the contacts 38 and 39 separated as above described in conjunction with the embodiment of Fig. 1. Thereby the operation of the starting switch is discontinued first by the mechanical opening of the contacts 38 and 39 and then by the retention of said contacts in open position by reason of the continued operation of the heater 42.

As in the embodiment of Fig. 1, it is only necessary when resetting the starting switch to deenergize the starting switch, as by interrupting the current supply through transformer 15 or removing the lamp 10 from its circuit.

It will therefore be perceived that the present invention provides means for discontinuing the operation of the starting switch of an electrical discharge lamp if the lamp be defective or otherwise fails to start. Said means for discontinuing

the operation of the starting switch operates automatically, and by properly proportioning the relationship of the bimetallic arms 28 and 40 with the associated finger 36 of Fig. 1, or the corresponding bimetallic arms 53 and 40 with the associated finger 36 of Fig. 2, it is possible to nicely predetermine the number of applications of transient voltage to the lamp 10 before the starting switch is rendered inoperative. It will further be perceived that the means provided for discontinuing the operation of the starting switch has the advantage that it is automatically reset to its normal operating condition upon deenergization of the switch, as by interrupting the current supply to the lamp or removing the lamp from the circuit or disconnecting the switch. Furthermore, the invention provides a relatively simple means for effecting the foregoing automatic operations, and one that may be associated with a lamp without unduly complicating the circuits or structure involved. By using a thermally operated switch that remains closed during the normal operation of the circuit and providing means for opening said switch and for energizing electrical means that retain the switch in open position upon the occurrence of abnormal conditions, as evidenced by a failure to start the lamp after a limited number of tries, danger of injury to the starting switch and its transformer, reactor and associated parts has been eliminated in a simple and efficient way that may be readily embodied in commercial starting switches.

While the embodiments of the invention illustrated on the drawings have been described with considerable particularity, it is to be expressly understood that the invention is not limited thereto as other circuit arrangements, other mechanical means for transmitting movement to or from the thermostatically operated switch, other electrical means energized upon an opening of the switch to retain the latter in its open position, etc., will now readily suggest themselves to those skilled in the art without departing from the principle of this invention. Reference is therefore to be had to the appended claims for a definition of the invention.

What is claimed is:

1. In a starting switch for electrical discharge lamps of the type having at least two electrodes, one at least of said electrodes being of the filamentary type and requiring an electrode heating current only during starting, in combination with normally closed contacts in circuit with the electrodes of said lamp and thermally operated means energized by closing the circuit through said lamp for separating said contacts, a second set of contacts closed by said thermally operated means if the lamp fails to start, said thermally operated means co-operating with said second named contacts to repeat the opening and closing of said circuit through said electrodes for applying a starting voltage thereto, and means actuated by the repeated operation of said second named contacts when said lamp fails to start for opening said circuit against continued operation, said last named means including a third set of contacts in circuit with said electrodes and mechanical means operated by said thermally operated means for separating said last named contacts.

2. In a starting switch for electrical discharge lamps of the type having at least two electrodes, one at least of said electrodes being of the filamentary type and requiring an electrode heating

current only during starting, in combination with normally closed contacts in circuit with the electrodes of said lamp, thermally responsive means for separating said contacts, a heating coil energized by completing the circuit through said lamp for actuating said thermally responsive means to separate said contacts and apply a starting voltage to said electrodes, a second set of contacts closed by said thermally responsive means if said lamp fails to start, said thermally responsive means co-operating with said last named contacts to open and close said circuit alternately and apply repeated starting voltages to said electrodes, a third set of contacts in circuit with said last named contacts and said electrodes, means mechanically actuated by repeated opening and closing of said second named contacts for opening said third named contacts, and means for maintaining said third named contacts in open position.

3. In a starting switch for electrical discharge lamps of the type having at least two electrodes, one at least of said electrodes being of the filamentary type and requiring an electrode heating current only during starting, in combination with normally closed contacts in circuit with the electrodes of said lamp, thermally responsive means for separating said contacts, a heating coil energized by completing the circuit through said lamp for actuating said thermally responsive means to separate said contacts and apply a starting voltage to said electrodes, a second set of contacts closed by said thermally responsive means if said lamp fails to start, said thermally responsive means co-operating with said last named contacts to open and close said circuit alternately and apply repeated starting voltages to said electrodes, a third set of contacts in circuit with said last named contacts and said electrodes, means actuated by repeated opening and closing of said second named contacts for mechanically opening said third named contacts, and electrical means energized by the opening of said last named contacts for retaining said last named contacts in open position.

4. In a starting switch for electrical discharge lamps of the type having at least two electrodes, one at least of said electrodes being of the filamentary type and requiring an electrode heating current only during starting, in combination with normally closed contacts in circuit with the electrodes of said lamp, thermally responsive means for separating said contacts, a heating coil energized by completing the circuit through said lamp for actuating said thermally responsive means to separate said contacts and apply a starting voltage to said electrodes, a second set of contacts closed by said thermally responsive means if said lamp fails to start, said thermally responsive means co-operating with said last named contacts to open and close said circuit alternately and apply repeated starting voltages to said electrodes, a third set of normally closed contacts in circuit with said last named contacts and said electrodes and adapted to be opened mechanically, means actuated by repeated opening and closing of said second named contacts for mechanically opening said third named contacts, and means whereby said third set of contacts is held open only by continuous energization of the starting circuit of said lamp.

5. In a starting switch for electrical discharge lamps of the type having at least two electrodes, one at least of said electrodes being of the filamentary type and requiring an electrode heating

current only during starting, in combination with normally closed contacts in circuit with the electrodes of said lamp, thermally responsive means for separating said contacts, a heating coil energized by completing the circuit through said lamp for actuating said thermally responsive means to separate said contacts and apply a starting voltage to said electrodes, a second set of contacts closed by said thermally responsive means if said lamp fails to start, said thermally responsive means co-operating with said last named contacts to open and close said circuit alternately and apply repeated starting voltages to said electrodes, a third set of contacts in series with said electrodes and second named contacts, thermally operated means actuated by the repeated opening and closing of said second named contacts, and mechanical means operated by said last named thermally operated means for separating said third set of contacts.

6. In a starting switch for electrical discharge lamps of the type having at least two electrodes, one at least of said electrodes being of the filamentary type and requiring an electrode heating current only during starting, in combination with normally closed contacts in circuit with the electrodes of said lamp, thermally responsive means for separating said contacts, a heating coil energized by completing the circuit through said lamp for actuating said thermally responsive means to separate said contacts and apply a starting voltage to said electrodes, a second set of contacts closed by said thermally responsive means if said lamp fails to start, said thermally responsive means co-operating with said last named contacts to open and close said circuit alternately and apply repeated starting voltages to said electrodes, a third set of contacts in series with said electrodes and second named contacts, thermally operated means actuated by the repeated opening and closing of said second named contacts, mechanical means operated by said last named thermally operated means for separating said third set of contacts, and electrical means energized by the opening of said last named contacts for retaining said last named contacts in open position.

7. In a starting switch for electrical discharge lamps of the type having at least two electrodes, one at least of said electrodes being of the filamentary type and requiring an electrode heating current only during starting, in combination with normally closed contacts in circuit with the electrodes of said lamp, thermally responsive means for separating said contacts, a heating coil energized by completing the circuit through said lamp for actuating said thermally responsive means to separate said contacts and apply a starting voltage to said electrodes, a second set of contacts closed by said thermally responsive means if said lamp fails to start, said thermally responsive means co-operating with said last named contacts to open and close said circuit alternately and apply repeated starting voltages to said electrodes, a third set of contacts in series with said electrodes and second named contacts, thermally operated means actuated by the repeated opening and closing of said second named contacts, mechanical means operated by said last named thermally operated means for separating said third set of contacts, and thermally responsive means energized by the opening of said third named contacts for maintaining said third named contacts open.

8. In a starting switch for electrical discharge

lamps of the type having at least two electrodes, one at least of said electrodes being of the filamentary type and requiring an electrode heating current only during starting, in combination with normally closed contacts in circuit with the electrodes of said lamp, thermally responsive means for separating said contacts, a heating coil energized by completing the circuit through said lamp for actuating said thermally responsive means to separate said contacts and apply a starting voltage to said electrodes, a second set of contacts closed by said thermally responsive means if said lamp fails to start, said thermally responsive means co-operating with said last named contacts to open and close said circuit alternately and apply repeated starting voltages to said electrodes, a third set of contacts in series with said electrodes and second named contacts, thermally operated means actuated by the repeated opening and closing of said second named contacts, mechanical means operated by said last named, thermally operated means for separating said third set of contacts, thermally responsive means carrying one of said third named contacts, and heating means energized by the opening of said third named contacts for retaining said last named thermally responsive means in the position in which said third named contacts are held open.

9. In a starting switch for electrical discharge lamps of the type having at least two electrodes, one at least of said electrodes being of the filamentary type and requiring an electrode heating current only during starting, in combination with normally closed contacts in circuit with the electrodes of the lamp, a bimetallic arm on which one of said contacts is mounted, a resistor in heat interchanging relationship with said arm and energized by the closing of the circuit through said electrodes to effect the flexure of said arm and the opening of said contacts to apply a starting voltage to said lamp, a second set of contacts associated with said arm and closed by said arm if said lamp fails to start, said resistor co-operating with said arm to open and close the circuit alternately through said second named contacts a plurality of times if the lamp fails to start, a third set of contacts in circuit with said second named contacts and said electrodes, a bimetallic arm adapted to actuate said third named contacts, and a heater progressively energized by the opening and closing of said second named contacts for flexing said last named arm and mechanically opening said third set of contacts.

10. In a starting switch for electrical discharge lamps of the type having at least two electrodes, one at least of said electrodes being of the filamentary type and requiring an electrode heating current only during starting, in combination with normally closed contacts in circuit with the electrodes of the lamp, a bimetallic arm on which one of said contacts is mounted, a resistor in heat interchanging relationship with said arm and energized by the closing of the circuit through said electrodes to effect the flexure of said arm and the opening of said contacts to apply a starting voltage to said lamp, a second set of contacts associated with said arm and closed by said arm if said lamp fails to start, said resistor co-operating with said arm to open and close the circuit alternately through said second named contacts a plurality of times if the lamp fails to start, a third set of contacts in circuit with said second named contacts and said electrodes, a bimetallic arm adapted to actuate

said third named contacts, a heater progressively energized by the opening and closing of said second named contacts for flexing said last named arm and mechanically opening said third set of contacts, and electrical means energized by the opening of said third contacts for retaining said third contacts in open position.

11. In a starting switch for electrical discharge lamps of the type having at least two electrodes, one at least of said electrodes being of the filamentary type and requiring an electrode heating current only during starting, in combination with a starting circuit including the electrodes of said lamp and means for alternately opening and closing said circuit to initiate the operation of said lamp, means for additionally controlling the operation of said starting circuit including additional contacts in circuit with said electrodes, means associated with said first named means for mechanically opening said last named contacts after a predetermined number of operations of said starting circuit at said first named means and means whereby said last named contacts are thereafter closed only upon deenergization of said starting circuit.

12. In a starting switch for electrical discharge lamps of the type having at least two electrodes, one at least of said electrodes being of the filamentary type and requiring an electrode heating current only during starting, in combination with a starting circuit including the electrodes of said lamp and thermally operated means for alternately opening and closing said circuit to initiate the operation of said lamp, and thermally responsive means for additionally controlling the operation of said starting circuit including contacts in series with said electrodes and means associated with said first named means for mechanically opening said last named contacts after a predetermined number of operations of said starting circuit at said first named means and to thereby initiate energization of said second named means to hold said last named contacts in open position.

13. In a starting switch for electrical discharge lamps of the type having at least two electrodes, one at least of said electrodes being of the filamentary type and requiring an electrode heating current only during starting, in combination with contacts in circuit with the electrodes of said lamp and means for alternately opening and closing said circuit to initiate the operation of said lamp, a second set of contacts in circuit with said electrodes, means associated with said first named means for mechanically opening said second set of contacts after a predetermined number of operations of said first named means, and electrical means adapted to maintain said second set of contacts thereafter in open position as long as said starting circuit is energized and to effect reclosure of said second set of contacts only upon deenergization of said lamp.

14. In a starting switch for electrical discharge lamps of the type having at least two electrodes, one at least of said electrodes being of the filamentary type and requiring an electrode heating current only during starting, in combination with normally closed contacts in series with the electrodes of said lamp and thermally operated means for alternately opening and closing said circuit to initiate the operation of said lamp, a heating coil for actuating said thermally operated means, a second set of contacts in series with said electrodes, thermally operated means for operating said second set of contacts, a heat-

ing coil associated with said second set of contacts, and means associated with one of said first named contacts for mechanically opening said second set of contacts to initiate energization of said last named heating coil to hold said set of contacts in open position.

15. In a starting switch for electrical discharge lamps of the type having at least two electrodes, one at least of said electrodes being of the filamentary type and requiring an electrode heating current only during starting, in combination with normally closed contacts in series with the electrodes of said lamp and thermally operated means energized by closing the circuit through said lamp for separating said contacts, a second set of contacts closed by said thermally operated means if the lamp fails to start, said thermally operated means cooperating with said second named contacts to repeat the opening and closing of said circuit through said electrodes for applying a starting voltage thereto, a third set of contacts in series with said electrodes, means for opening said third set of contacts, and thermally operated means for holding said third set of contacts open once said contacts have been opened.

16. In a starting switch for electrical discharge lamps of the type having at least two electrodes, one at least of said electrodes being of the filamentary type and requiring an electrode heating current only during starting, in combination with normally closed contacts in series with the electrodes of said lamp and thermally operated means energized by closing the circuit through said lamp for separating said contacts, a second set of contacts closed by said thermally operated means cooperating with said second named contacts to repeat the opening and closing of said circuit through said electrodes for applying a starting voltage thereto, a third set of contacts in series with said electrodes, and thermally responsive means cooperating with one of said second set of contacts and actuated by the repeated opening and closing of said second set of contacts for mechanically opening the circuit at said third set of contacts.

17. In a starting switch for electrical discharge lamps of the type having at least two electrodes, one at least of said electrodes being of the filamentary type and requiring an electrode heating current only during starting, in combination with normally closed contacts in series with the electrodes of said lamp and thermally operated means energized by closing the circuit through said lamp for separating said contacts, a second set of contacts closed by said thermally operated means if the lamp fails to start, said thermally operated means cooperating with said second named contacts to repeat the opening and closing of said circuit through said electrodes for applying a starting voltage thereto, a third set of contacts in series with said electrodes, means for opening said third set of contacts, and thermally operated means which are normally short circuited by said third set of contacts for holding said third set of contacts open.

18. In a starting switch for electrical discharge lamps of the type having at least two electrodes, one at least of said electrodes being of the filamentary type and requiring an electrode heating current only during starting, in combination with normally closed contacts in series with the electrodes of said lamp and thermally responsive means energized by closing the circuit through said lamp for separating said contacts, a second

set of contacts closed by said thermally responsive means if the lamp fails to start, said thermally responsive means cooperating with said second named contacts to repeat the opening and closing of said circuit through said electrodes for applying a starting voltage thereto, a third set of contacts in series with said electrodes actuated by thermally responsive means, means for opening said third set of contacts, and heating means normally short circuited by said third set of contacts and comprising a heating coil in series with the electrodes adapted to hold said last named contacts open following opening thereof.

19. In a starting switch for electrical discharge lamps of the type having at least two electrodes, one at least of said electrodes being of the filamentary type and requiring an electrode heating current only during starting, in combination with normally closed contacts in series with the electrodes of said lamp, thermally responsive means

energized by closing the circuit through said lamp for separating said contacts, a second set of contacts closed by said thermally responsive means if the lamp fails to start, said thermally responsive means cooperating with said second named contacts to repeat the opening and closing of said circuit through said electrodes for applying a starting voltage thereto, a third set of normally closed contacts in series with said electrodes, thermally responsive means cooperating with one of said second set of contacts and actuated by the repeated opening and closing of said second set of contacts for mechanically opening the circuit at said third set of contacts, and thermal means normally short circuited by said third set of contacts and comprising a heating coil in series with said starting circuit for maintaining said third set of contacts in open position.
